UNITED STATES PATENT OFFICE.

LUM M. HEFLIN, OF SONORA, TEXAS.

PUMP-CYLINDER PROTECTOR.

Application filed February 17, 1923. Serial No. 619,611.

To all whom it may concern:

Be it known that I, LUM M. HEFLIN, a citizen of the United States, residing at Sonora, in the county of Sutton and State 5 of Texas, have invented certain new and useful Improvements in Pump-Cylinder Protectors, of which the following is a specification.

The present invention relates to pump 10 cylinder protectors which prevent the gravitation of extraneous materials or objects into the cylinder.

It is well known in the art to provide 15 various types of cylinder protectors which function in a manner similar to the device of the present invention. However, it is an object of this invention to provide a protector for the cylinder which is retained beyond the confines of the latter to eliminate 20 possibility of the protector interfering with the normal use of the pump and furthermore to prevent the protector from contacting with the cylinder walls and from scoring or otherwise mutilating the latter.

Another object of the invention is to provide 25 a protector of this type so constructed that the water may pass freely therethrough with little or no possibility of the passageways in the protector becoming clogged in view of the especial construction of these 30 passages.

Other objects of the invention will be apparent 35 from the following description of the present preferred form of the invention taken in connection with the accompanying drawings wherein:—

Fig. 1 is a vertical sectional view of a 40 protector constructed in accordance with this invention illustrating its application;

Fig. 2 is an elevational view partly in 45 section of the cylinder protector per se; and Fig. 3 is a top plan view thereof.

In the drawings a pump cylinder 4 is shown which may be of the usual or any desired 50 configuration. A piston 5 is slidably mounted in the cylinder and has the rod 6 thereof extending upwardly beyond the upper terminal of the cylinder. A pipe 7 is superimposed on the upper end of the cylinder 55 the diameter of the bore of which is in excess of the diameter of the bore of the cylinder. The cylinder 4 and pipe 5 are detachably connected together by a screw-threaded collar 8. The upper end of the

piston rod 6 is equipped with a screw-threaded shank 9 which is engaged by a corresponding socket 10 formed on the lower end of a plunger rod 11, the latter being connected to a windmill in a manner well known in the art.

The protector per se consists of a substantially semi-spherical body 12 the bottom 13 of which is flat and is provided with a central opening 14 through which the shank 9 of the piston rod 6 passes. The body is provided, adjacent its upper margin, with a circular series of openings 15 each of which communicates with a vertically extending channel or passageway 16. These channels have their inception at a point approximately midway the upper and lower margins of the protector body and gradually become deeper until they ultimately merge into the openings 15 thereby reducing frictional resistance, of the water being elevated, to a minimum. The protector is held from displacement on the rod 6 by the plunger rod 11, the socket end of the latter being threaded on the shank 9, above the flat end 13 of the protector 12. It will be noted that the upper 80 end of the protector radiates into close proximity to the inner periphery of the pipe 7 to eliminate possibility of objects passing between the outer periphery of the protector and the inner periphery of the pipe.

The location of the protector is of importance in the present invention since it has been found by practical experience that cylinder protectors, which operate within the cylinder, score or otherwise mutilate the 90 walls of the latter in time, with the result that the efficiency of the pump is prematurely mitigated. It has also been found that by locating the protector above the cylinder, as in the present instance, that not only will the cylinder be saved from mutilation by the protector or by objects which fall into the latter, but moreover, the water is elevated in a more effective manner and the protector is more readily accessible for cleaning the same. Where the protector is mounted within the cylinder, especially in deep wells, it has a tendency at times to jar the bolts loose. The construction and arrangement of the water passageways in the protector is also of importance in the present invention.

Various changes may be made in this de-

vice, especially in the details of construction, proportion and arrangement of parts within the scope of the claim hereto appended.

What is claimed:—

- 5 A pump cylinder protector including a protector body engageable with the pump piston rod, said protector being of semi-

spherical configuration and provided with an annular series of openings adjacent its upper margin each of which communicates ¹⁰ with a water passageway in the outer face of the body, substantially as described.

LUM M. HEFLIN.
